UNITED STATES PATENT OFFICE

ROBERT S. PEELLE, OF HOLLIS, NEW YORK, ASSIGNOR TO THE PEELLE COMPANY, OF BROOKLYN, NEW YORK, A CORPORATION OF NEW YORK

OPERATOR FOR COUNTERBALANCED ELEVATOR DOORS

Application filed April 5, 1930. Serial No. 441,918.

My invention relates to operators for counterbalanced elevators doors, and more particularly to an operator of the type in which each door in an elevator shaft may be 5 opened or closed by means of an electric motor located within the shaft, means being provided whereby an electric current from a source may be selectively applied to any motor in the shaft to the exclusion of all other 10 motors.

Elevator doors of the type to which the operator of my invention is adapted to be applied include two vertically and oppositely movable counterbalanced sections slidable 15 upon a guide structure mounted upon the wall of the shaft adjacent the door openings, flexible connections extending from one of these sections to the other and passing over sheaves adjacent the lintel of the door opening and secured to the guide rail structure. The space available adjacent the shaft for the installation of such doors amounts only to a few inches, and the conditions within an 20 elevator shaft make the installation of the doors difficult and expensive since the door equipment must be adapted to the requirements of the elevator car and the structure within the shaft incidental to its operation.

In the installation of elevator door equipment, the guide structure is produced in the factory with the sheaves, tracks, stops, etc., completely and permanently assembled 25 therein. The guide rails are bolted to the wall of the shaft, the section of the rail adjacent each opening being accurately positioned in relation to the sill of the opening by means of certain guide markings upon the rail structure.

With the above conditions in mind, I have 30 produced an electric motor actuated operator, the construction of which is such as to admit of the motor and of the means of transmitting power therefrom to a sheave being mounted directly upon the rail structure 35 while in the factory, and installed in the shaft as an incident to the installation of the rail structure, thus avoiding any necessity for any machine assembly work by the erection gang.

In the construction above referred to, the

various parts are not only so constructed as to secure a desired speed in the movement of the door sections, even though a high speed motor may be used, but as to so position the speed reducing gear train for the transmission of power from the motor to the sheave as to avoid any cutting of the flanges of the guide rail structure and yet bring the motor, the gear transmission and the sheaves within a compass avoiding any substantial extension 55 of any of the operator mechanisms within the shaft beyond the guide rail structure itself. The location of the sheaves upon the guide rail structure is predetermined by the construction and type of door, and the operator motor and the transmission mechanism connecting same with the sheave, must be adapted to conditions determined by the door and the guide rail structure.

With the operator of my invention, all of 60 the power transmission system is positioned within the thickness of the guide rail structure, and the only portion of the operator mechanism adjacent the door which extends beyond this guide rail is a portion of the 65 motor. By using a speed reducing mechanism, a small motor having low H. P. may be employed, thus limiting the extent of its projection beyond the guide rail structure. 70 One portion of the gear train is located between the sheave and the wall of the shaft, and the other portion thereof is carried by, and located immediately adjacent, the sheave upon the shaft side thereof, thus dividing the 75 space required for this mechanism, and not 80 only securing ample space for the different gears, but adapting the gearing to the characteristics of the guide rail structure and bringing all portions thereof, excepting a 85 small part of one gear which is attached to 90 the sheave at one side of the guide rail structure where there can be no interference with the operation of the door. Furthermore, by 95 this construction, it is possible to adapt the motor and the power transmission mechanism actuated therefrom to a guide rail structure and an arrangement of the sheave demanded by conditions other than those required by the operator.

It is essential, in an elevator door struc- 100

ture, not only that the construction be so simple as to practically eliminate all possibility of disarrangement of parts under normal operating conditions, notwithstanding the severe usage to which said doors are subjected, but that the operator of my invention shall have the various parts so constructed and arranged as to require practically no attention beyond an occasional oiling and greasing, and be so assembled as to make it impossible for anyone to interfere with the proper adjustment and relation of parts, this being determined by the assembly of the operator and the rail structure in the shop.

15 The invention consists primarily in an operator for counterbalanced elevator doors embodying therein the combination with a guide rail structure within an elevator shaft, a series of elevator doors each having sections vertically and oppositely movable on said structure, connections between said sections on the opposite sides thereof, and sheaves about which said connections pass, of an electric motor secured to said guide rail structure within the shaft, a speed reducing gear train, the first gear of which is connected with the shaft to said motor, and the last gear of which is connected directly with a sheave, a main electric power line extending adjacent all of said doors, a branch line extending therefrom adjacent each door and connected with the motor adjacent such door, a normally open switch in each of said branch lines adapted to be operated only when a car is positioned adjacent said switch, pole changing switches controlling the circuits to said main power line, electro-magnetic control mechanisms for said pole changing switches, and means whereby said control mechanisms may be selectively actuated from a remote point; and in such other novel features of construction and combination of parts as are hereinafter set forth and described, and more particularly pointed out in the claims hereto appended.

45 Referring to the drawings,

Fig. 1 is a view from the shaft side of elevator doors at two adjacent openings, said view being laterally and vertically condensed;

Fig. 2 is a view of a fragmentary portion of the guide rail structure adjacent the sheave of a door showing the motor and gear train of the operator associated therewith;

Fig. 3 is a view from the right of Fig. 2; Fig. 4 is a plan view of Fig. 2; and

Fig. 5 is a diagrammatic showing of one form of electrical control system capable of use with the operator of my invention.

Like numerals refer to like parts throughout the several views.

In the embodiment of the invention shown, the operator is applied to doors closing openings at two adjacent floors. The construction of each of these doors, the parts ap-

purtenant thereto and of the operator used in connection therewith are identical, so that a description of but one of these doors and its operator is necessary, the reference numerals being applied to the corresponding parts of the other door.

A counterbalanced door is shown in the drawings, although the invention is also applicable to pass type doors of different constructions, and in fact to any door located in an elevator shaft using a plurality of counterbalanced sections, one of which moves upwardly and the other downwardly along a guide rail structure mounted in the shaft.

In the drawings, the upper door section is shown at 10, the lower section at 11 and the chains or other flexible connections secured adjacent the bottom of the section 10 and the top of the section 11, at 12. Each of these chains 12 passes over a sheave 13 located above the upper door section and, as will more fully appear hereinafter, secured to the guide rail structure. One end of each chain 12 is connected in the usual manner to a hanger bar 14 forming a part of the top bar structure of the lower section 11.

The sections 10 and 11 are slidable upon tracks 15 forming a part of the guide structure, such tracks usually being carried by what is known as a wall angle 16, one flange of which is adapted to be bolted to the wall of the building, and the other flange of which extends inwardly of the shaft. This guide rail structure usually extends throughout the entire height of the shaft in operative relation to all of the doors in the shaft. Its details may be varied according to the detailed construction or type of the door itself. Secured to the guide rail structure, at opposite sides of each door opening, are adjustable stops 17, so positioned in relation to the sill of a door opening as to bring the top bar of the lower section at rest on substantially the plane of the sill of the door opening.

Also co-operating with the hanger bar 14 are lock members 18 of an old and well known construction.

The features above referred to are all old and well known in the freight elevator door art, and are herein shown and described as typical of a door having those characteristics which present the problems necessary to be solved by the application of a motor actuated operator thereto. The same characteristics are found in doors to which other types of operators are applied.

The above description is limited to those structural characteristics of the door necessary to an understanding of the operation of the operator of my invention and of the doors equipped therewith. Consequently, other details of the door structure and of the various mechanisms referred to will not be described.

In the operator of my invention shown in

the drawings, the power from the motor is applied only to one of the sheaves 13, the other sheave, that shown at the left of Fig. 1, being of the usual and well known construction. This application of power to only one sheave is permissible with counterbalanced doors of narrower widths, although with heavier and wider doors the operator mechanism may be duplicated upon opposite sides of the door.

In the embodiment of the invention shown in the drawings, I provide one of the sheaves 13 with a spur gear 19, which preferably forms an integral part, and one of the shrouds, of the sheave, the chain 12 co-operating with this sheave being seated between this gear and the other shroud of the sheave. The shaft 20 upon which the sheave is mounted, preferably by means of ball bearings, is carried by a bracket 21 provided with lugs 22, by means of which it may be mounted upon a plate 23 carried by and bolted to the wall angle 16 of the guide rail structure.

The sheave 13 is positioned inwardly of the shaft in relation to the guide or track structure 15, and projects through an opening in the plate 23 as shown in the drawings, said gear being in substantially the plane of the edge of the inwardly directed flange of the inner edge of this plate.

Also mounted in the bracket 21 is a shaft 24, ball bearings also being used for this shaft. Carried by said shaft is a small gear 25 enmeshed with the gear 19, and a large gear 26 positioned between the fitting 21 and the wall of the shaft, as shown in Figs. 3 and 4. It will be noted that this gear 26 is positioned between the sheave 13 and the wall of the shaft, or in what in the ordinary counterbalanced door construction, is an unused space adjacent the guide rail structure.

Mounted upon the top of the bracket 21 is a small motor 27 which may be of any desired construction which will permit the reversal of its direction of rotation under suitable controls. Upon the shaft of this motor is mounted a small gear 28 enmeshed with the gear 26.

In all elevator doors there is always ample space at the side of the guide rail structure, and there is seldom much available space between the guide rail structure and the elevator car, although some space at this point is always available since certain clearance is required between the platform of the car and the wall of the shaft, particularly in those installations where the fire underwriters or a building department requires doors of a certain minimum thickness and a certain construction to be used.

The type of door immediately above referred to may range from two to four inches in thickness, and the available space adjacent the wall of the shaft and inwardly thereof may be six or eight inches. This

limited space has offered a very serious problem, the solving of which has prevented the use of electric motor actuated operators, and when such operators have been used, they have either been what is known as "pent-house" operators, or have been located upon the floor side of the shaft and required the drilling of holes in the wall to permit the transmission of power from the motor to the sheaves.

I have heretofore developed an operator of the general type to which my present invention relates, in which the motor is geared directly to the sheave. I have found it desirable, however, to provide a speed reducing gearing between the motor and the sheave, and the inclusion of such a mechanism offered very serious difficulties by reason of the lack of available space.

In connection with the operator mechanism above described, it is essential to provide an electrical control mechanism by which any motor 27 in a shaft may have power applied thereto to turn it in either direction and thus apply either opening or closing movement to the door. The specific arrangement of such a control mechanism forms no part of my present invention, although its use is essential to a successful use of the operator. I have shown in Fig. 5 of the drawings, a diagram illustrating an electrical control device, capable of use with the other characteristics of the operator shown, this being a remote control including a pole changing switch mechanism 29 in the main line supplying power to any motor 27 in a shaft.

I also provide in this control mechanism a time limit switch 30, by which the duration of the actuation of the motor is determined. At 31 I have shown an ordinary car switch mechanism controlling the circuits from the source 32 to the holding magnets 33 and 34 of the pole changing mechanism 29. At 35 I have illustrated a shaft switch mechanism adapted to be actuated by a cam carried by the elevator car controlling the circuit from the main electric power line 36 to the motor 27. There is a shaft switch 35 adjacent each door opening in a shaft which controls a branch circuit 37 to the motor 27 of the operator for the door at such opening. The shoe of the car for controlling the switch 35 is shown at 38.

This circuit control mechanism is capable of various refinements, a description of which is unnecessary to an understanding of the present invention, which relates more particularly to the use, in a counterbalanced door operator, of a particular construction of motor actuated power transmitting means, the current to the motor of which is under the influence of a remote control mechanism of the general type above described.

The operation of the herein described operator is substantially as follows:—

Under normal operating conditions, all doors in a shaft are closed, and it is essential that a car be located at some particular opening, before the door at that opening can be actuated by the operator of the invention. This is controlled by the shaft switch 35 and the car cam 38. The actuation of the switch 35, however, merely permits the application of power to the motor, and its actuation alone will merely establish a condition by which other controls may be set so as to complete the circuit through this switch to the motor 27.

The general type of remote control shown in the drawings need be described only generally. When a car is brought to rest at a door opening, the operator actuates the car switch 31, thus closing the circuit through the time limit switch 30 to the holding magnet 33 of the mechanism 29. The energizing of this magnet closes the circuit from the source 32 to the main line 36, thus completing the circuit to the motor 27. When power is applied to this motor, it is transmitted through the small gear 28 upon the motor shaft to the large gear 26 upon the shaft 24. The turning of this shaft 24 transmits power through the small gear 25 carried thereby to the large gear 19 upon the sheave 13, thus turning this sheave at a low speed compared with the motor speed, but at a speed sufficiently high to ensure a rapid opening movement of the door.

The chain 12 or other flexible connection merely frictionally engages the sheave 13, and the results secured by the construction herein described arise solely from the fact that the two sections 10 and 11 of the door have a counterbalancing action one on the other, so that the load upon the motor is so small as to permit the utilization of a motor of low H. P. and of small dimensions. The doors themselves may weigh from four to five hundred pounds, or even more, and yet the motor 27 has only a fraction of a H. P. and its overall dimensions may be only a few inches.

The frictional engagement between the chains 12 and the sheaves 13 is not essential so far as the application of power for opening or closing the door is concerned, but this frictional engagement introduces two very desirable functions in the operator, the first of which is to supplement the action of the time limit switch in preventing injury to the door or operator structure as a result of overrunning of the motor upon the completion of either the opening or the closing movement of the door. This is of minor importance, however, since the time limit switch may be so set as to cut off the power to the motor before the door has reached either the fully opened or the fully closed position, the

moving inertia of the counterbalanced door sections completing either the opening or the closing movement without the application of power thereto.

In the event of the failure of the time limit switch, however, the engagement of the hanger bar 14 on the lower door section with the stops 17 relieves the chain upon one side of the sheave and connected with said hanger bar, from the load of this section and causes slippage of the sheave in relation to the chains, notwithstanding the continued application of power to the sheave. This, however, is a mere precautionary feature.

When the two sections come together upon the closing movement, the same slippage will occur since the chain upon the other side of the sheave will be relieved of the load of the upper section.

The main advantage of the frictional engagement between the chains and the motor actuated sheave, is that in the event of the failure of any motor from any reason whatsoever, the door may still be operated manually, the chain either having slippage in relation to its sheave, or actuating the speed reducing mechanism and the motor so as to permit the free opening or closing movement of the door.

Because of this condition, no interruption of the elevator service need result from the failure of the operator as to any door in the shaft, and the failure of any one operator will not require any servicing as to any of the other operators. If the trouble be in the remote controls, the only servicing required is as to that control, and during such servicing the elevator service may be maintained and access may be had therefrom to any floor of the building by the manual actuation of the doors.

By reason of this capability of the operator, none of the clutch or other mechanisms, usually provided for the purpose of permitting the operator to be made inoperative in relation to all of the doors in a shaft, is required.

The locking members 18, whether in the form shown in the invention, or in any other desired form, are employed to prevent the opening of a door from the floor side of a shaft at all times excepting when an elevator car is opposite the opening closed by the door to be opened, and hence these locks cooperate with the operator of the invention in preventing manual operation of the doors from the floor of a building which, except for such locks, might be possible with the construction of operator described.

As stated above, the time limit switch controls the circuit to the holding magnet for a predetermined interval at the expiration of which the circuit to the motor will be automatically interrupted by this switch. The time limit switch is included only in the circuit closed for the purpose of opening the

door, the switch mechanism for applying power to the motor for closing the door being a positive pressure switch, or one in which the operator must maintain the switch in the closed position during the full closing movement of the door excepting for that movement as a result of the moving inertia of the two sections above referred to.

The manner of supporting the motor, the speed reducing power transmission gearing and the sheave, by, and in a predetermined relation to, the guide rail structure, are matters of primary importance, and as this has been heretofore pointed out, it is desired to merely add that the construction and arrangement of parts herein referred to, is such as to secure a ratio of speed of the sheave and of the motor shaft to impart the desired rate of travel of the door section during the opening and closing of the door, by a mechanism located in its entirety within the limited space available, and without any modification whatever in the guide rail or the door structure excepting the addition to the sheave 13 of the gear 19 and a change in the construction of the support for this sheave, or the substitution of the bracket 21 for the usual sheave housing.

It is not my intention to limit the invention to the precise details of construction shown in the drawings, it being apparent that such may be varied without departing from the spirit and scope of the invention.

While in the drawings, I have shown the use of a single motor operative upon one sheave only, it is obvious that this mechanism may be duplicated upon opposite sides of the door if desired.

Having described the invention, what I claim as new and desire to have protected by Letters Patent, is:—

1. An operator for counterbalanced elevator doors embodying therein the combination with a guide rail structure within an elevator shaft, a series of elevator doors each having sections vertically and oppositely movable on said structure, connections between said sections on the opposite sides thereof, and sheaves about which said connections pass, of an electric motor secured to said guide rail structure within the shaft, a speed reducing gear train, the first gear of which is connected with the shaft to said motor, and the last gear of which is connected directly with a sheave, a main electric power line extending adjacent all of said doors, a branch line extending therefrom adjacent each door and connected with the motor adjacent such door, a normally open switch in each of said branch lines adapted to be operated only when a car is positioned adjacent said switch, pole changing switches controlling the circuits to said main power line, electro-magnetic control mechanisms for said pole changing switches, and manually opera-

tive switch mechanisms controlling the circuits to the windings of the magnets of said control mechanisms whereby said control mechanisms may be selectively actuated from a remote point.

2. An operator for counterbalanced elevator doors embodying therein the combination with a guide rail structure within an elevator shaft, a series of elevator doors each having sections vertically and oppositely movable on said structure, connections between said sections on the opposite sides thereof, and sheaves about which said connections pass, of a bracket in which said sheave is mounted secured to said guide rail structure, a large gear carried by said sheave, a shaft counter to the shaft of said sheave and having a small gear thereon enmeshed with said gear carried by the sheave, and a large gear thereon positioned between said sheave and the wall of the shaft, a motor supported by said bracket, a small gear upon the shaft of said motor enmeshed with said large gear, a main electric power line extending adjacent all of said doors, a branch line extending therefrom adjacent each door and connected with the motor adjacent such door, a normally open switch in each of said branch lines adapted to be operated only when a car is positioned adjacent said switch, pole changing switches controlling the circuits to said main power line, electro-magnetic control mechanisms for said pole changing switches, and manually operative switch mechanisms controlling the circuits to the windings of the magnets of said control mechanisms whereby said control mechanisms may be selectively actuated from a remote point.

3. An operator for counterbalanced elevator doors embodying therein the combination with a guide rail structure within an elevator shaft, a series of elevator doors each having sections vertically and oppositely movable on said structure, connections between said sections on the opposite sides thereof, and sheaves about which said connections pass, of a bracket in which said sheave is mounted secured to said guide rail structure, a large gear carried by said sheave, a shaft counter to the shaft of said sheave and having a small gear thereon enmeshed with said gear carried by the sheave, and a large gear thereon positioned between said sheave and the wall of the shaft, a motor mounted upon the top of said bracket above said sheave, a small gear upon the shaft of said motor enmeshed with said large gear, a main electric power line extending adjacent all of said doors, a branch line extending therefrom adjacent each door and connected with the motor adjacent such door, a normally open switch in each of said branch lines adapted to be operated only when a car is positioned adjacent said switch, pole changing switches controlling the circuits to said main power line, electro-magnetic control mechanisms for said pole changing switches, and manually opera-

line, electro-magnetic control mechanisms for
said pole changing switches, and manually
operative switch mechanisms controlling the
circuits to the windings of the magnets of
said control mechanisms whereby said control
mechanisms may be selectively actuated from
a remote point.

In witness whereof I have hereunto affixed
my signature, this 31st day of March, 1930.

ROBERT S. PEELE.
